(57) CLAIM

The ornamental design for a nursing garment, as shown and described.

DESCRIPTION

FIG. 1 is a perspective view of a nursing garment showing my new design.

FIG. 2 is a front elevational view thereof.

FIG. 3 is a rear elevational view thereof.

FIG. 4 is a side elevational view thereof.

FIG. 5 is a top plan view thereof.

FIG. 6 is a bottom plan view thereof.

FIG. 7 is a first perspective view shown in position of use with environment; and,

FIG. 8 is a second perspective view shown in position of use with environment.

The broken lines in the drawings are for the purpose of illustrating environment only and form no part of the claimed design.
